UNITED STATES PATENT OFFICE.

WALDERMA C. SCHAUFLER, OF AMSTERDAM, NEW YORK.

ELECTRICAL EXERCISING APPARATUS.

938,399.

Specification of Letters Patent.

Patented Oct. 26, 1909.

Application filed July 9, 1908. Serial No. 442,729.

To all whom it may concern:

Be it known that I, WALDERMA C. SCHAUFLER, a citizen of the United States, residing at Amsterdam, in the county of 5 Montgomery and State of New York, have invented certain new and useful Improvements in Electrical Exercising Apparatus, of which the following is a full, clear, and exact description, such as will enable others 10 skilled in the art to which it appertains to make and use the same.

This invention relates to electrical exercising apparatus.

One of its objects is to provide means for 15 producing currents of electricity through the body or limbs of the operator, combined with means for physical exercise another object being to avoid the use of the weights which are usually employed, another object 20 being to simplify and improve the construction of an apparatus of this type.

Other objects will be in part obvious and in part pointed out hereinafter.

The invention accordingly consists in the 25 features of construction, combinations of elements and arrangement of parts which will be exemplified in the construction hereinafter set forth, and the scope of the application of which will be indicated in the 30 following claims.

In the accompanying drawings, there is shown an illustrative embodiment of the invention, in which the reference numerals refer to similar parts in the several figures.

35 Figure 1 is a perspective view of the apparatus ready for use. Fig. 2 is a front elevation of the same, with the casing removed, parts being shown in section for the sake of clearness. Fig. 3 is a top plan view of the 40 apparatus. Fig. 4 is a diagrammatic representation of the various circuits. Fig. 5 is an enlarged detailed view of the automatic circuit closing means, and Fig. 6 is a sectional view of the elastic cord, showing in 45 part an elevational view of the inner covering.

In the illustrative embodiment of the invention shown in the drawings, 1 and 2 indicate the handles which are made of conducting material, in order to serve as electrodes 50 for conveying the current to the hands of the operator. Attached to these handles are elastic cords 3 and 4, which consist of rubber or other similar material 5 provided 55 with a plurality of coverings, the outer covering 6 being preferably of non-conducting

material, and the inner covering comprising one or more tortuous strands of electrical conducting material 7, so arranged as to permit the elastic cords to be extended and retracted without danger of said strands being ruptured, and these strands are in electrical contact with the handles. As the parts which coöperate with each of these cords are similar in all respects, those relating to one 60 cord only will be described, the same reference numeral being used to designate similar parts in both instances. From the handle the cord leads over guide pulley 8, which is mounted on a bracket 9, provided with an 65 extension 10 which is slidably mounted within the sleeve 11, which may be supported upon a suitable bracket 12 secured to the base 13 of the apparatus. The free end of the extension 10 engages with the free end of 70 the spring contact 14, which is preferably secured to the bracket 12 as shown in Fig. 5. When the parts are in their normal positions, the free end of the spring contact is 75 out of engagement with its coöperating fixed contact 15, and holds the pulley and its bracket in their raised or upper positions as shown in Fig. 5. When the apparatus is being used, the pressure exerted by the cords upon the pulleys will force them into their 80 inner or lower positions, at the same time forcing the free end of the spring contact into engagement with its coöperating fixed contact, as shown in Fig. 2, to close an electric circuit for the purpose hereinafter to be 85 described.

After passing over the guide pulley, the cord passes through a suitable opening in the casing, and then passes around a plurality of grooved pulleys 16—17, and has 90 its other end secured to a suitable insulating support 18, which may be supported by the bracket 12. The grooved pulleys are constructed of non-conducting material, and one of them as 16 carries upon its outer surface a series of contacts 19 arranged about its center in the circumference of a circle. Bearing upon the outer surface of the pulley and in the line of travel of the contacts 19, carried thereby in order to be engaged therewith as the pulley rotates, are a pair of spring contacts 20—21, as clearly shown in Fig. 2. A suitable source of electricity 22, such as a dry cell, is preferably mounted upon the base and has one of its poles, connected by wire 23 with the wire 24, the ends 100 of which are in an electrical connection with

the spring contacts 14. The other pole of the cell is connected by wire 25 to one end of the primary coil 26 of the induction coil 27, which is also preferably mounted upon 5 the base. The other end of the primary coil is connected by a wire 28 with a wire 29, the ends of which are connected with the member 20 of each of the pairs of contacts 20—21, the other member 21 of each 10 of said pairs of contacts being connected by wires 30 to the fixed contact members 15. One end of the secondary coil 31 of the induction coil 27 is connected by a wire 32 with the conductor 7 contained within the 15 elastic cord 4, and the other terminal of said secondary coil is connected to the wire 25 which leads from the battery to the primary coil. A wire 33 connected with wire 29 leads to the conductor 7 contained within 20 the elastic cord 3, all of these connections being indicated in the diagrammatic representation illustrated in Fig. 4.

The operation of the device will now be explained. When the apparatus is not in use, the spring contacts 14 will as stated above occupy their normal positions out of contact with the fixed contacts 15, thus providing a positive break in the primary circuits, irrespective of the relative position 30 of the traveling contacts 19 with respect to their coöperating pair of spring contacts 20—21. When the operator grasps the handles for the purpose of exercising, and pulls thereon, the guide pulleys 8 will be forced 35 into their power positions, as above described, thereby forcing the spring contacts 14 against the fixed contacts 15 to complete the battery circuit at these points. As the cords are extended and retracted during the 40 operation of the apparatus they will cause the pulleys 16 and 17 to rotate, and as the pulleys 16, which carry the contacts 19, rotate, these contacts will pass beneath and contact with their coöperating pair of 45 spring contact members 20—21, thus causing the primary circuit to be made and broken, the current flowing over the following path beginning with the battery 22, wire 23, wire 24, spring contact member 14, fixed contact member 15, wire 30 through 50 each of the contact members 20—21, which at that instant will be electrically connected by means of one of the contacts 19, and then by wire 29 to wire 28, thence through the primary coil 26 and back to the battery by wire 25, there being a corresponding path 55 closed by the traveling contacts upon the other pulley. As the circuit is made and broken a current will be induced in the secondary coil in the well-known manner, which current will flow over the following path beginning with handle 2, thence through the electric conductor 7 contained within the elastic cord 4, then by wire 32, 60 to one terminal of the secondary coil 31,

through said coil to the wire 25, thence through the primary coil 26, wire 28, wire 29, wire 33, to the conducting member 7 contained within the elastic cord 3 to the handle 1, this circuit of course being completed through the body or limbs of the person exercising. The induction coil is provided with the usual core 34, which may be withdrawn or inserted therein, in order to produce a stronger or weaker current in the 75 secondary coil as desired in the well-known manner.

As many changes could be made in the above construction and many apparently widely different embodiments of this invention could be made without departing from the scope thereof, it is intended that all matter contained in the above description or shown in the accompanying drawings shall be interpreted as illustrative and not in a 85 limiting sense. It is also to be understood that the language used in the following claims is intended to cover all of the generic and specific features of the invention herein described and all statements of the scope of 90 the invention which, as a matter of language, might be said to fall therebetween.

Having described my invention what I claim as new and desire to secure by Letters Patent, is:

1. In an electric exercising apparatus, in combination, an exercising cord, a source of electricity, a circuit therefor, a plurality of circuit controlling devices in said circuit, and a plurality of means for actuating said 100 circuit controlling devices, each of said means being operatively engaged by said cord whereby when tension is applied to said cord said circuit controlling devices will be actuated.

2. In an electric exercising apparatus, in combination, an exercising cord, a guide-pulley coöperating with said cord, a bracket supporting said guide-pulley, a sleeve within which said bracket is slidably mounted, and a circuit controlling device adapted to be operated by the movement of said bracket 110 when tension is applied to said cord and to cause said bracket to assume its normal position when said tension is removed.

3. In an electric exercising apparatus, in combination, elastic cords, comprising electrical conducting means, guide pulleys co-operating with said cords, brackets supporting said guide pulleys, sleeves within which 120 said brackets are slidably mounted, and circuit-controlling devices adapted to be operated by the movement of said brackets, when tension is applied to said cords, and to cause said brackets to assume their normal positions when said tension is removed.

4. In an electric exercising apparatus, in combination, elastic cords, comprising electrical conducting means, guide pulleys co-operating with said cords, brackets support- 130

ing said pulleys, sleeves within which said brackets are slidably mounted, fixed contact members adjacent each of said brackets, spring contacts coöperating with each of 5 said fixed contact members and normally out of contact therewith, said spring contacts normally engaging with the said brackets to hold them in their normal positions and adapted to be moved into engagement 10 with said fixed contact members by the movement of said brackets.

5. In an electric exercising apparatus, in combination, cords comprising electrical conducting means, movably mounted pulleys 15 coöperating with said cords, rotatable members with which said cords engage whereby movement thereof will rotate said members, a source of electricity, an induction coil, a circuit between said source of electricity and 20 said coil normally open at two points, means controlled by the movement of one of said pulleys to close the circuit at one of its normally open points, and means controlled by one of the rotatable members to close 25 the circuit at the other of its normally open points.

6. In an electric exercising apparatus, in combination, elastic cords comprising electrical conducting means, movably mounted 30 pulleys coöperating with said cords, rotatable members with which said cords engage whereby movement thereof will rotate said members, a source of electricity, an induction coil, a circuit between said source of 35 electricity and said coil normally open at two points, means controlled by the movement of one of said pulleys to close the circuit at one of its normally open points, and means controlled by one of the rotatable 40 members to close the circuit at the other of its normally open points.

7. In an electric exercising apparatus, in combination, cords comprising electrical conducting means, movably mounted pulleys co- 45 operating with said cords, rotatable members with which said cords engage whereby

movement thereof will rotate said members, a source of electricity, an induction coil, circuits between said source of electricity and said induction coil normally open at two 50 points, means controlled by the movement of said pulleys to close each circuit at one of its normally open points, and means controlled by said rotatable members to close each circuit at the other of its normally open 55 points.

8. In an electric exercising apparatus, in combination, elastic cords comprising electrical conducting means, movably mounted pulleys coöperating with said cords, rotatable 60 members with which said cords engage whereby movement thereof will rotate said members, a source of electricity, an induction coil, circuits between said source of electricity and said induction coil normally 65 open at two points, means controlled by the movement of said pulleys to close each circuit at one of its normally open points, and means controlled by said rotatable members to close each circuit at the other of its nor- 70 mally open points.

9. In an electrical exercising apparatus, in combination, a base, elastic cords having one end secured thereto and comprising electrical conducting means, members rotatably 75 supported upon said base with which said cords engage, pulleys slidably mounted upon said base adapted to guide said cords, a source of electricity, an induction coil, circuits between said source and said coil, each 80 of which is normally open at two points, means controlled by said pulleys to close said circuits at one of their normally open points, and means controlled by said rotatable members to close said circuits at the 85 other of their normally open points.

In testimony whereof I affix my signature, in the presence of two witnesses.
